DESIGN FOR A BOTTLE

Caroline G. Humphreys, Forest Hills, N. Y.

Application March 6, 1934, Serial No. 50,957

Term of patent 14 years

To all whom it may concern:

Be it known that I, CAROLINE G. HUMPHREYS, a citizen of the United States of America, residing at 45 Exeter Street, Forest Hills, in the county of Queens and State of New York, have invented a new, original, and ornamental Design for a Bottle, of which the following is a specification, reference being had to the accompanying drawing, forming a part thereof, and showing in—

Fig. 1 a perspective front view, and in Fig. 2 a top plan view of the bottle embodying my design.

I claim:

The ornamental design for a bottle substantially as shown.

CAROLINE G. HUMPHREYS.
